RAILWAY SKATE

Samuel Jones Beck, McLouth, Kans.

Substitute for abandoned application Serial No. 461,489, October 11, 1954. This application September 15, 1958, Serial No. 762,195

9 Claims. (Cl. 104—260)

This invention relates to improvements in skates or that class of railway equipment used in the braking of railway cars by the provision of apparatus adapted to fit over and upon the rail and to slide therealong when the railway car rolls upon the skate itself.

More particularly, the instant invention relates to railway equipment in the nature of that set forth in my U. S. Patent 2,782,728 and having for its primary object the provision of improvements upon the skate for railway cars therein disclosed and claimed.

The instant application constitutes a substitute for my abandoned application Serial No. 461,489 filed Oct. 11, 1954.

It is the most important object of the present invention to provide a railway skate having means for holding the same upon the rail so that, when contacted by the car wheel, it will not become displaced, which holding means is fully and completely retractable as the skate skids along the rail in response to contact with frogs and other projections or abutments forming a part of the rail.

In this connection, it is to be pointed out that conventional railway skates are inadequate because of the failure to include rail-embracing means for positively holding the same in place until the railway car actually rolls thereupon. The omission of such holding or clamping means have been omitted for the reason that rails are not entirely free from obstructions along the side edges thereof and any depending projection on the skate coming into engagement with frogs and the like would be completely unsatisfactory because of breakage to the skate itself, as well as the frog, and because of the nature of derailment.

In my U. S. patent above-mentioned, there is provided a skate having releasable rail clamping means operable automatically as the car wheel rolls thereupon and for the most part, such clamping means, when thus released, clears all projections on the rail except the said frogs.

It is an important object of the instant invention therefore, to incorporate the principles of the invention disclosed in my U. S. patent and to combine therewith clamping means especially adapted for automatically clearing the frogs as the jaws forming a part of the clamp, come into contact therewith.

Another object of this invention is to provide a railway skate having a pair of opposed clamping jaws that not only shift upwardly to a position clearing the frogs and other abutments when the jaws are moved into engagement therewith, but which are adapted to swing outwardly in much the same manner as disclosed in my U. S. patent in response to the weight of the railway car when one of its wheels rolls upon the skid bar of the skate.

Additional objects include the way in which the clamping jaws of the skate are mounted for swinging movement on horizontal axes independently of each other so that when the leading end thereof engages a frog or other projection, it will first tip on its axis of swinging movement and thereupon rise to a position completely clearing the said frog; the way in which the opposed jaws are inter-

2

connected by spring means permitting not only utilization of structure for separating the same out of clamping engagement with the rail, but permitting the jaws to rise to a position engaging hooks that maintain the jaws in an elevated position until reset for subsequent use; and many additional objects including important details of construction, all to be made clear as the following specification progresses.

In the drawings:

10 Figure 1 is a side elevational view of a railway skate made pursuant to my present invention showing the same operably mounted on a rail and illustrating a car wheel resting thereon.

15 Fig. 2 is a top plan view of the railway skate mounted on a rail.

Fig. 3 is a longitudinal, cross-sectional view taken on line III—III of Fig. 2.

Fig. 4 is an end elevational view of the skate showing the rail in section.

20 Fig. 5 is an elevational view showing the opposite end of the skate and illustrating the rail in cross-section.

Fig. 6 is a vertical, cross-sectional view taken on line VI—VI of Fig. 1.

25 Fig. 7 is an enlarged, fragmentary, detailed, cross-sectional view taken on line VII—VII of Fig. 1; and

Fig. 8 is an enlarged, fragmentary, detailed, cross-sectional view taken on line VIII—VIII of Fig. 2.

30 Skate 10 forming the subject matter of the instant invention, is shown in the drawings operably mounted on a rail 12, and in Figure 1, a car wheel 14 is shown fragmentarily in position upon the skate 10 engaging a substantially triangular-shaped abutment 16 extending upwardly from and forming an integral part of an elongated skid bar 18. The skid bar 18 which engages directly 35 with the uppermost face of the rail 12 upon which the skate 10 rests, has an end 20 flared upwardly as best seen in Figs. 1 and 3, permitting the skate 10 to slide along the rail 12 without danger of catching on projections such as frequently occur, especially at rail joints.

40 The hollow abutment 16 is provided with a handle 22 for ease in carrying and means 23 is provided on the abutment 16 for releasably clamping the skate 10 to the rail 12 until such time as the wheel 14 rolls upon the skid bar 18 and particularly upon an elongated actuator bar 24 having a ramp-like tongue 26 at its forwardmost end extending beyond the proximal end of the skid bar 18.

45 The skid bar 18 is provided with a longitudinal, upwardly facing groove 28 for clearing the bar 24 and a pivot pin 30 adjacent the tongue 26 swingably connects the bar 24 to the skid bar 18 for swinging movement on a horizontal axis. Bar 24 extends through an opening 32 in the front face of the abutment 16 and terminates in a spreading or separating head 34 for jaws 36 and 38 of said clamping means 23.

50 Jaws 36 and 38 are identical and include an elongated strap 40 having inclined ends 41 and having heads 42 on the innermost faces thereof normally held in engagement with the sides of rail 12, as best seen in Figs. 4 to 6 inclusive by springs 44 extending through the abutment 16 and interconnecting the jaws 36 and 38. Springs 44 extend through openings 45 in the sides of abutment 16 and are connected to upstanding ears 46 integral with the strap 40 and the latter is likewise provided with an integral, upstanding stem 48 between the ears 46 thereof, which stem 48 is T-shaped, presenting a hinge pin 50 at the uppermost end thereof and spaced above the ears 46 and the springs 44.

55 The springs 44 constitute the sole means for mounting the clamping means 23 upon the abutment 16 and, therefore, there is provided opposed slots 52 in abutment 16 slidably and rotatably receiving inwardly extending pintles 54 integral with the stems 48 adjacent the hinge pins 50.

It is now appreciated that the springs 44 serve to yieldably hold the hinge pins 50 biased against the opposed outermost sides of the abutment 16 and to maintain the pintles 54 within the slots 52 for vertical reciprocation and rotation on horizontal axes, all for purposes herein-after to be made clear.

Such manner of interconnecting the jaws 36 and 38 and attaching the same to the abutment 16, permits upward movement of the jaws 36 and 38 to a position where the hinge pins 50 thereof engage within hooks 56 on the opposed sides of abutment 16. Hinge pins 50 are guided upwardly and outwardly and into the hooks 56 by inclined faces 58 terminating at their lowermost ends in elongated horizontal concavities 60 parallel with the hooks 56 and normally receiving the hinge pins 50 in the manner illustrated by dotted lines in Fig. 6 of the drawings. As is clear in Fig. 1, the slots 52 intersect the hooks 56 and the concavities 60 to clear the inwardly extending pintles 54 for free vertical movement with respect to the abutment 16.

As seen in Fig. 3 of the drawings, the actuating bar 24 is provided with a loop 62 within the abutment 16 that clears the proximal spring 44 and the head 34 is disposed beneath the pintles 54 for movement between inwardly extending spreading members 64 integral with the stems 48 of the jaws 36 and 38 and aligned vertically with the pintles 54 therebeneath.

As seen in Fig. 6 of the drawings, the innermost ends of the separator members 64 are preferably inclined and, therefore, as the bar 24 is swung downwardly from the position shown in Fig. 3 by the weight of wheel 14 resting thereon, head 34 moves toward and skid bar 18 between the separators 64, causing the jaws 36 and 38 to swing outwardly away from each other with the hinge pins 50 rotating within their seats or concavities 60. Noteworthy is the fact that when the wheel 14 moves upon the bar 24 to swing the head 34 thereof downwardly about pivot pin 30, the tongue 26 swings upwardly away from the rail 12 so that the same does not slide on the rail 12 and become damaged and worn ahead of normal deterioration of the skate itself. On the other hand, when the skate 10 is seated and ready for use as shown in Fig. 3, the tongue 26 engages the rail 12 and receives the wheel 14 without danger of catching and consequent damage to the skate or derailment thereof.

Notwithstanding such arrangement of the tongue 26 and the provision of the clamping means 23 for holding the skate 10 on the rail, it may be desirable in some instances to provide auxiliary means to hold the skate 10 in place, particularly along the skid bar 18 remote from abutment 16 so as to maintain the tongue 26 in proper alignment with the oncoming wheel 14. Such auxiliary holding means is illustrated in Figs. 1, 2, 7 and 8 and includes a pair of wings 66, one on each side of the skid bar 18 and rigid to stub shafts 68 mounted on the skid bar 18 for rotation on horizontal axes. Each stub shaft 68 has an out-turned flange 70 on the innermost end thereof rotatable within an annular groove 72 formed in the skid bar 18 and in a U-shaped retainer 74 that is releasably secured to the uppermost face of the skid bar 18 to hold the stub shaft 68 in place. Intermeshing teeth or serrations 76 are formed on the outermost face of the flange 70 and on the proximal faces of skid bar 18 and retainer means 74 as seen in Figs. 7 and 8, and a spring 78, housed within the stub shaft 68 at the innermost end thereof, yieldably holds the flange 70 biased outwardly to interengage the serrations 76.

When the skate 10 is placed in use, it is positioned upon the rail 12 through use of handle 22 in the manner illustrated by Figs. 2 to 6 inclusive, with the heads 42 engaging the sides of the rail 12 and the hinge pins 50 seated within their concavities 60. Bar 24 is in the position shown by Fig. 3 with head 34 raised and the tongue 26 engaging rail 12. And, the wings 66 are turned down-

wardly in embracing relationship to the sides of the rail 12 as seen in Figs. 1, 2 and 7.

As soon as the wheel 14 rolls upon the tongue 26 and thence upon the bar 24 and the skid bar 18, the head 34 is swung downwardly toward the bar 18, spreading the jaws 36 and 38. It is seen that head 34, acting upon the inclined innermost ends of the spreaders 64, swings the jaws 36 and 38 against the action of springs 44 as the hinge pins 50 rotate within their concavities 60.

When the wheel 14 engages the abutment 16, the skate 10 is immediately advanced along the rail 12 and as the bar 18 skids therealong, the up-turned or flared end 20 thereof, clears all projections and the tongue 26 is held out of engagement with the rail 12 as shown in Fig. 1.

In the event the skate 10 encounters a frog or other projection along the sides of the rail 12 and the inclined end 41 of either or both of the jaws 36 or 38 come into engagement with such obstruction, such jaw immediately swings on its pintle 54 counterclockwise, viewing Fig. 1,

and as the lowermost edge of the strap 40 thereof passes over the frog, the entire jaw will be raised with respect to the abutment 16 to a position where the hinge pin 50 thereof moves into the corresponding hook 56. Such retention of the jaw above the level of the frog or other

protuberance, prevents the jaw from falling back to a position where it would tend to catch the frog and become torn off prior to complete clearance of such projection.

As soon as the wings 66 contact the frog they will be swung out of the way as the stub shafts 68 rotate and as the springs 78 permit rotation of the flange 70 notwithstanding the presence of serrations 76. Such serration will however, hold the wings 68 swung upwardly away from the frog because of the biasing action of springs 78.

When the skate 10 is again to be placed in use upon rail 12, the operator can easily remove the hinge pins 50 from the hooks 56 and re-position the same in the concavities 60 so that the heads 42 engage the sides of the rail 12 when bar 24 is raised to the position shown in Fig. 3. Similarly, the operator may swing the two wings 66 downwardly to a rail-embracing position as shown in Figs. 1, 2 and 7.

Having thus described the invention what is claimed as new and desired to be secured by Letters Patent is:

1. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting on the bar, said jaws engaging opposite sides of the abutment for vertical sliding movement therealong, and being provided with means normally disposed below the level of said skid bar in engagement with the sides of the rail; spring means interconnecting the jaws for holding the same in said engagement with the abutment and the rail, said abutment being provided with vertical guide means for said jaws; means on the jaws engaging in said guide means for restraining the jaws to vertical movement along the abutment upon engagement of said jaws with obstructions along the rail such as to raise the jaws above the normal rail-engaging position thereof while the bar skids along the rail, carrying the wheel; and hook means on the abutment disposed to receive the jaws as they move to the uppermost ends of their paths of travel.

2. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting on

the bar, said jaws engaging opposite sides of the abutment for vertical sliding movement therealong, and being provided with means normally disposed below the level of said skid bar in engagement with the sides of the rail; spring means interconnecting the jaws for holding the same in said engagement with the abutment and the rails, said abutment being provided with vertical guide means for said jaws; and means on the jaws engaging in said vertical guide means for restraining the jaws to vertical movement along the abutment upon engagement of said jaws with obstructions along the rail such as to raise the jaws above the normal rail-engaging position thereof while the bar skids along the rail, carrying the wheel.

3. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting on the bar, said jaws having horizontal hinge pins engaging opposite sides of the abutment for vertical sliding movement therealong, and being provided with means normally disposed below the level of said skid bar in engagement with the sides of the rail; spring means interconnecting the jaws for holding the same in said engagement with the abutment and the rails, said pins being disposed for swinging movement of the jaws outwardly away from said sides of the rail and away from each other against the action of said spring means and about said pins as fulcrums, said abutment being provided with vertical guide means for said jaws; and means on the jaws engaging in said guide means for restraining the jaws to vertical movement along the abutment upon engagement of said jaws with obstructions along the rail such as to raise the jaws above the normal rail-engaging position thereof while the bar skids along the rail, carrying the wheel.

4. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting on the bar, said jaws engaging opposite sides of the abutment for vertical sliding movement therealong, and being provided with means normally disposed below the level of said skid bar in engagement with the sides of the rail; spring means interconnecting the jaws for holding the same in said engagement with the abutment and the rails, said abutment being provided with vertical guide means for said jaws; means on the jaws engaging in said guide means for restraining the jaws to vertical movement along the abutment upon engagement of said jaws with obstructions along the rail such as to raise the jaws above the normal rail-engaging position thereof while the bar skids along the rail, carrying the wheel; and an actuating element mounted on the skid bar for vertical swinging movement, said element having means disposed for movement between the jaws when the element is swung downwardly whereby to spread the jaws apart against the action of said spring means and out of engagement with said sides of the rail, said element overlying the skid bar within the path of travel of said wheel for downward movement thereby as the wheel rolls upon said element and against said abutment.

5. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting on the bar, said jaws having horizontal hinge pins engag-

5

ing opposite sides of the abutment for vertical sliding movement therealong, and being provided with means normally disposed below the level of said skid bar in engagement with the sides of the rail; spring means interconnecting the jaws for holding the same in said engagement with the abutment and the rails, said pins being disposed for swinging movement of the jaws outwardly away from said sides of the rail and away from each other against the action of said spring means and about said pins as fulcrums, said abutment being provided with vertical guide means for said jaws; means on the jaws engaging in said guide means for restraining the jaws to vertical movement along the abutment upon engagement of said jaws with obstructions along the rail such as to raise the jaws above the normal rail-engaging position thereof while the bar skids along the rail, carrying the wheel; and an actuating element mounted on the skid bar for vertical swinging movement, said element having means disposed for movement between the jaws when the element is swung downwardly whereby to swing the jaws apart and out of engagement with said sides of the rail, said element overlying the skid bar within the path of travel of said wheel for downward movement thereby as the wheel rolls upon said element and against said abutment.

6. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting on the bar, said jaws engaging opposite sides of the abutment for vertical sliding movement therealong, and being provided with means normally disposed below the level of said skid bar in engagement with the sides of the rail; spring means interconnecting the jaws for holding the same in said engagement with the abutment and the rails, said abutment being provided with vertical guide slots for said jaws; and horizontal pintles on the jaws engaging in said guide slots for restraining the jaws to vertical movement along the abutment upon engagement of said jaws with obstructions along the rail such as to raise the jaws above the normal rail-engaging position thereof while the bar skids along the rail, carrying the wheel, said pintles being vertically slidable in the slots, tiltable in the slots to permit swinging of the jaws toward and away from each other, and rotatable in the slots to permit the jaws to rise at one end thereof as such one end engages an obstruction.

7. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting on the bar, said jaws engaging opposite sides of the abutment for vertical sliding movement therealong, and being provided with means normally disposed below the level of said skid bar in engagement with the sides of the rail; spring means interconnecting the jaws for holding the same in said engagement with the abutment and the rails, said abutment being provided with vertical guide slots for said jaws; horizontal pintles on the jaws engaging in said guide slots for restraining the jaws to vertical movement along the abutment upon engagement of said jaws with obstructions along the rail such as to raise the jaws above the normal rail-engaging position thereof while the bar skids along the rail, carrying the wheel, said pintles being vertically slidable in the slots, tiltable in the slots to permit swinging of the jaws toward and away from each other, and rotatable in the slots to permit the jaws to rise at one end thereof as such one end engages an obstruction; and an actuating element

75

mounted on the skid bar for vertical swinging movement, said element having means disposed for movement between the jaws when the element is swung downwardly whereby to spread the jaws apart against the action of said spring means and out of engagement with said sides of the rail, said element overlying the skid bar within the path of travel of said wheel for downward movement thereby as the wheel rolls upon said element and against said abutment.

8. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting on the bar, said jaws having horizontal hinge pins engaging opposite sides of the abutment for vertical sliding movement therealong, and being provided with means normally disposed below the level of said skid bar in engagement with the sides of the rail; spring means interconnecting the jaws for holding the same in said engagement with the abutment and the rails, said pins being disposed for swinging movement of the jaws outwardly away from said sides of the rail and away from each other against the action of said spring means and about said pins as fulcrums, said abutment being provided with vertical guide slots for said jaws; and horizontal pintles on the jaws engaging in said guide slots for restraining the jaws to vertical movement along the abutment upon engagement of said jaws with obstructions along the rail such as to raise the jaws above the normal rail-engaging position thereof while the bar skids along the rail, carrying the wheel, said pintles being vertically slideable in the slots, tilttable in the slots to permit swinging of the jaws toward and away from each other, and rotatable in the slots to permit the jaws to rise at one end thereof as such one end engages an obstruction, said abutment being provided with horizontal concavities normally receiving the hinge pins.

9. In a skate for use as a brake beneath a railroad car wheel, a skid bar adapted to receive the wheel in supporting relationship thereto and to slide along a rail for said wheel while supporting the latter; a releasable rail clamp having a pair of opposed jaws; an upstanding abutment rigid to the bar between the jaws and disposed for engagement by said wheel when the latter is resting

on the bar, said jaws having horizontal hinge pins engaging opposite sides of the abutment for vertical sliding movement therealong, and being provided with means normally disposed below the level of said skid bar in engagement with the sides of the rail; spring means interconnecting the jaws for holding the same in said engagement with the abutment and the rails, said pins being disposed for swinging movement of the jaws outwardly away from said sides of the rail and away from each other against the action of said spring means and about said pins as fulcrums, said abutment being provided with vertical guide slots for said jaws; and horizontal pintles on the jaws engaging in said guide slots for restraining the jaws to vertical movement along the abutment upon engagement of said jaws with obstructions along the rail such as to raise the jaws above the normal rail-engaging position thereof while the bar skids along the rail, carrying the wheel, said pintles being vertically slideable in the slots, tilttable in the slots to permit swinging of the jaws toward and away from each other, and rotatable in the slots to permit the jaws to rise at one end thereof as such one end engages an obstruction, said abutment being provided with horizontal concavities normally receiving the hinge pins, and hooks disposed to receive the hinge pins when the jaws are moved to the uppermost ends of their vertical paths of travel by said obstruction.
